UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,024,157.

Specification of Letters Patent.

Patented Apr. 23, 1912.

Application filed December 31, 1909. Serial No. 535,744.

To all whom it may concern:

Be it known that I, HERBERT H. STEELE, citizen of the United States, and resident of Marcellus, in the county of Onondaga and 5 State of New York, have invented certain new and useful Improvements in Type-Writing Machines, of which the following is a specification.

My invention relates especially to ribbon 10 mechanism for typewriting machines and its general object is to provide improved devices of the class specified.

To the above and other ends my invention 15 consists in the features of construction, combinations of devices and arrangements of parts hereinafter described and particularly pointed out in the claims.

In certain classes of typewritten records, 20 for example in some system of railway billing, it is necessary to provide for as many as twelve or fourteen copies of the work. Ordinarily this duplication of copies is 25 accomplished by the employment of carbon inlays between the work sheets, and this method has been found to be satisfactory in cases where the entire writing on the pack 30 of paper, comprising the alternate work sheets and carbon inlays, is to be completed at one time and without the pack being removed from the machine until the work is 35 done. There are, however, other forms of multiple record work in which the pack of work sheets and inlays must be removed and re-entered a number of times in the machine 40 before the record on said sheets has been completed. Heretofore it has been customary in such cases to bind the pack together by fasteners or clips in order to prevent displacement of any of the sheets during removal and entering. This is objectionable, 45 however, as consuming considerable time, first, in adjusting the carbon inlays between the work sheets; secondly, in binding the pack and, thirdly, in removing the carbon inlays from between the finished records. Furthermore, if the sheets are large and the 50 paper thin, the trouble experienced in maintaining even an approximately regular and uniform alinement in the undermost sheets of the pack is very great. On the other hand, it has not hitherto been possible to provide a typewriter inking ribbon which is capable of delivering sufficient ink to a 55 work sheet when the latter is printed to enable said work sheet to reproduce its im-

pressions on as many as twelve or fourteen tissue sheets in a copying press. Six or seven good reproductions seem to be about the limit of the inking ribbon, whereas a pen written copy or master sheet is capable of reproducing as many as twelve or fourteen copies in the copying press.

To overcome the disadvantages of the typewriter work in respect of the number of copies which may be reproduced therefrom, it is contemplated in the present instance to provide a supplemental ribbon at the rear face of the work sheet so that the impact of the types will be reproduced on the front of said sheet from a main copying 65 ink ribbon which is mounted and fed in the usual way while simultaneously the rear face of the work sheet will receive the type impressions from the supplemental ribbon. It will be apparent that the negative im- 70 pressions on the rear face of the work sheet will be in register with the positive impressions on the front face thereof. Thus the printed characters will be visible on each 75 side of the sheet and each side of the sheet 80 will have sufficient ink to penetrate six or seven tissue copies so that it is only necessary to place the typewritten work sheet or master sheet in the middle of a pile of 85 twelve or fourteen tissue sheets and take copies thereon by means of a copying press operated in the ordinary way.

In carrying out my invention in the present instance I provide an inked web or ribbon sheet having a width substantially equal 90 to the printing field of the way bill or work sheet. This web is wound upon spools which are contained within a hollow casing or drum having the same diameter as the regular cylindrical platen of the machine which said drum replaces. The drum also contains an anvil or platen face which operates with the types through a slit or opening extending longitudinally of the hollow casing. Each ribbon spool is geared to 95 a shaft which extends through the hollow casing and corresponds with the usual platen shaft, being controlled for line spacing by pawl and ratchet mechanism. Hand operated devices for changing the direction of 100 the ribbon feed are provided, and associated with these devices are automatic means for indicating when the reversing devices should be actuated. Said automatic means 105 comprises an abutment which is adapted to co- 110

operate with the paper table to prevent the insertion of a fresh work sheet prior to the actuation of the ribbon reversing mechanism. The work sheet is fed around the hollow casing by feed rollers of the usual or any suitable type which coöperate with rotary casing sections contiguous to the ends of the main stationary casing. The slot or opening in the stationary casing through which the types strike is only wide enough to afford clearance for the types so that only a small amount of the auxiliary ribbon is exposed. The feeding devices for said auxiliary ribbon are adjusted to operate at each line spacing operation so as to advance said auxiliary ribbon a distance corresponding substantially to the width of a line of writing.

The details of my preferred construction 20 will be more clearly understood from a consideration of the accompanying drawings which show one form of the invention applied to a Monarch typewriting machine and wherein,

25 Figure 1 is a transverse sectional view of the upper part of a Monarch typewriting machine embodying my invention. Fig. 2 is a transverse section taken on a plane represented by the dotted line *x* in Fig. 6 and looking in the direction of the arrow at said line. Fig. 3 is a transverse sectional view on a plane represented by the dotted line *y* in Fig. 6 and looking in the direction of the arrow at said line. Fig. 4 is a front elevation of the hollow casing or drum and associate parts. Fig. 5 is a fragmentary horizontal sectional view taken centrally of the hollow casing, some of the parts shown in Fig. 4 being omitted. Fig. 6 is a fragmentary vertical sectional view taken centrally of the hollow casing.

Referring first to Fig. 1, a top plate 1 of the machine supports standards 2 to which are secured grooved guide rails 3 in which 45 are seated anti-friction balls 4. Said balls coöperate with longitudinal grooves formed at the top and bottom of a rear or slide bar 5, said bar being comprised in a platen frame or carrier of the long platen style, and which 50 further includes end bars 6. The end bars 6 provide bearings for an axle or shaft 7 like the usual platen shaft, said shaft 7 being provided at its ends with finger wheels 8.

Through intermediate devices hereinafter 55 described the shaft 7 provides bearings for two disks or heads 9 which are spaced apart a distance somewhat greater than the length of the lines of writing of the work for which the structure is intended. Secured at its 60 ends to these disks 9 is a cylindrical hollow casing or drum 10, the diameter of which corresponds to that of the usual rotary platen whose position in the machine said casing occupies as clearly appears from Fig. 1, 65 which is a sectional view taken about mid-

way of the length of the casing 10. The casing proper extends from a point below the printing point at the front of the machine in a downward, rearward and upward circular curve terminating under the usual paper finger rod 11 which is supported on the end bars 6 and provides an anchor for the casing. Stays in the form of sheet metal hooks 12 are arranged at intervals along the rod 11 as shown in Fig. 4, said hooks partly surrounding said rod and having rearward and downward extending portions 12^a which are riveted or otherwise secured to the casing 10 and hold the same from turning relatively to the axle 7. The rod 11 also provides bearings for the hinges 13 of a cover plate 14, the hinges being secured to said cover plate as by rivets 15, the cover plate thereby being adapted to be swung on the rod 11 as a pivot. The rear end of the cover plate abuts against the end of the casing 10 which underlies the rod 11 and said cover plate is concentric with the casing, being practically a continuation thereof and extending downward to within a short distance of the printing line. 90

It will be noted more especially from Figs. 1 and 4 that there is a gap or longitudinal slot-way 16 in the casing opposite the printing point, said gap extending between the bottom edge of the cover 14 and the top 95 edge of the front of the casing proper and being of a width slightly in excess of the heights of the type characters. Practically filling the gap widthwise and extending the full length thereof, is an anvil or platen 17 100 which tapers toward the rear and is provided with clip 18, said clips engaging the shaft 7 and securing the platen 17 thereto. The body portion of the platen is rounded at its top and bottom edges, but it terminates 105 at its ends in rectangular enlargements 17^a which are seated in slots 19 (Fig. 1) formed in the disks 9. These slots prevent rotary movement of the platen about the axle 7. The clips 18 permit the platen to be readily 110 detached and removed from the casing when the cover thereof is lifted but when arranged as shown in Fig. 1 the platen will be stationary with respect to the casing and has only a longitudinal movement during the advance 115 and the return of the platen carrier.

A wide ribbon or web 20 impregnated with copying ink and having a width somewhat greater than the length of the printing line is provided, said ribbon is suitably 120 secured at its ends to shafts 21 and 22 arranged respectively above and below the axle 7, said shafts having reduced end portions or extensions 21^a and 22^a which take bearings in the disks or heads 9 as shown in 125 Fig. 6. Arranged on the reduced ends of these shafts and abutting the body portions thereof are removable flanges 23, each pair of flanges 23 and the body portions of the associate shafts 21 and 22 constituting a 130

ribbon spool, the ribbon 20 being adapted to be wound on and unwound from said body portions as hubs and being confined between said flanges 23.

5 The ribbon spools are connectible to the shaft 7 so as to receive motion therefrom when said shaft is turned, the connections comprising for each shaft a pair of gear wheels 24 mounted one outside of each flange 10 23 on a reduced end portion of the shaft and suitably secured thereto. Each gear wheel 24 is provided with hubs or collar portions 24^a and as shown in Fig. 6 is arranged between the contiguous flange 23 and the adjacent face of one of the disks 9. It will be further observed from Fig. 6 that the corresponding gears of the two spools are out of line or register with each other, this arrangement being effected by turning the collar portions 24^a of the corresponding gear wheels in opposite directions. The gear wheels 24 are adapted to be driven by a pair of gear wheels 25, each gear wheel 25 being mounted on a sleeve 26 which is slidably supported on the shaft 7. The disks 9 are provided with hub portions 9^a through which the sleeves 26 pass and slidably fit, the construction being such that each disk 9 bears on the associate sleeve 26. Each gear wheel 25 is secured to the inner reduced end portion 26^a of the associate sleeve 26, this reduced portion between the gear 25 and the body of the sleeve providing clearance for the teeth of the associate gear wheels 24. 35 The left-hand sleeve 26 is formed with an elongated slot 27 and the right-hand sleeve 26 with a corresponding slot 28. A short pin 29 fixed to the shaft 7 engages the slot 27 and a longer screw pin 30 secured in the shaft 7 engages with the slot 28. The pin and slot connections between the shaft 7 and the sleeves 26 compel said sleeves to participate in rotary movements communicated to said shaft while permitting endwise movement of said sleeves relatively to said shaft. 40 The two sleeves are held in fixed relationship to each other lengthwise of the shaft and are adapted to be moved along said shaft simultaneously for the purpose of connecting and disconnecting the driving gears 25 with and from the spool gears by devices which comprise a pair of bifurcated arms 31, each bifurcated arm partially embracing one of the sleeves 26 and being arranged between a pair of spaced flanges 32 on said sleeve as shown in Figs. 3, 5 and 6. As will be clearly understood from Fig. 5 the flange portions of the sleeves 26 extend outward and beyond the hub portions of the heads 50 9 and are arranged exteriorly of the stationary casing 10. It will also be seen that the bifurcated arms 31 are exterior of the casing 10. The arms 31 extend horizontally rearward and each terminates in a collar portion 33 which engages with a slide rod

34, being suitably secured thereto as by a pin 35. The slide rod extends through the casing 10 behind and parallel with the shaft 7 and bears near its ends in the disks or heads 9. Said slide rod may be moved endwise by a finger piece 36 (Figs. 3 and 5), said finger piece having a collar portion 37 which surrounds and is suitably secured to the rod 34, the finger piece proper extending upward through a slot in the casing 10 and being operative from outside said casing. It will be understood that at one time the driving wheels 25 are maintained in mesh with the gears at the ends of the upper ribbon spool so that if the shaft or 70 axle 7 were rotated its motion will be communicated to the upper ribbon spool to wind the ribbon 20 thereon and unwind it a corresponding extent from the lower ribbon spool which is disconnected from the shaft. Further it will be apparent that if the slide rod 34 be shifted leftward by the finger piece 36, it will operate to slide the sleeves 26 leftward along the shaft 7 so as to disengage the driving gears 25 from the upper spool 75 gears and bring said driving gears into mesh with the two lower spool gears, thus adapting the lower spool to turn and wind ribbon thereon. Thus provision is made for reversing the direction of longitudinal feed of the ribbon 20 so that it may be fed alternately back and forth between the two spools. 80

From Fig. 1 it will be understood that the ribbon 20 is led from the under side of the hub of its lower spool upward and forward over the rounded lower edge of the platen 17, thence passing upward over the front or printing face of said platen over the rounded upward edge thereof and thence rearward and upward to the under side of the hub of the upper ribbon spool. The printing face of the platen 17 is concentric with the casing and is slightly within the curvature of the casing so that the printing portion of the ribbon 20 overlying said face will not project beyond the casing, the ribbon being thus well protected against accidental contact with the paper or hands of the operator. Furthermore, as only a small portion of the length of the ribbon is exposed at one time opposite the slot-way, the liability of the rear face of the work sheet to smut from contact with said ribbon is minimized. 100

In order to indicate to the operator when the winding ribbon spool is full and when the direction of ribbon feed should be reversed, I provide devices comprising a curved block 38 of wood which bears on the slide rod 34 and is provided near its ends with bearing plates 39 which partly embrace the rod 34 and are secured to the block 38 as by rivets 125 40. The block 38 is adapted to swing freely on the rod 34 as a pivot and is normally maintained by gravity in the position shown 130

in Fig. 1. Endwise movement of the block 38 is limited by collars 41 fixed to the rod 34 as shown in Fig. 5. The construction and disposition of the block 38 is such that when the coils of ribbon 20 on the winding ribbon spool reach a predetermined diameter the ribbon will frictionally engage with the curved face of the block 38 and will turn said block on its pivot 34 in the direction of the arrow in Fig. 1.

Overlying the rear upper side of the casing 10 as shown in Fig. 1 is a curved plate 42, said plate being provided at its upper side with ears 43 which are curled around the rod 11 and serve to connect pivotally the plate 42 therewith. Angularly disposed portions 42^a are bent inward from the lower edge of the plate 42 passing through slots 44 in the casing 10 and contacting with the block 38 above the pivot thereof. The construction is such that when the block 38 is swung on its pivot 34 as above described it will act to swing the plate 42 rearward and upward on its pivot 11 and will bring the lower edge portion of said plate into the path over which the work sheets are introduced into the machine, thus blocking the introduction of a new work sheet and notifying the operator that the ribbon 20 should be reversed. When this reversal has been accomplished by the actuation of the finger piece 36 the operator next presses the plate 42 back to normal position, causing the angular portions 42^a to turn the block 38 back to normal position.

As clearly shown in Figs. 5 and 6, the peripheries of the disks 9 project outward beyond the ends of the fixed casing 10. The projecting portions of the disks provide bearings for movable tubular sections 45 and 46 which are in effect continuations of the fixed casing 10, being of the same diameter but which unlike the casing 10 are adapted to be rotated when the shaft or axle 7 is turned. The left-hand end portion of the device or rotary tube 45 bears on the periphery of a head 47, said head being provided with an inwardly extending hub 48 which is secured to the shaft 7 by a screw pin 49, said screw pin as shown in Fig. 6 connecting the rotary tube 45, the hub 48 and the shaft 7 so that they will all three turn together. The member comprising the head 47 and hub 48 may be of the construction found in the platen releasing mechanism of the Monarch typewriter and such as is disclosed in the pending application of Hubbard N. Josley, Serial No. 335,430, filed Sept. 20th, 1906. A line spacing ratchet wheel 50 bears on the outward projections 47^a on said head 47 and is or may be normally connected with said head by releasable devices shown in said Josley application. The right-hand device or rotary tube 46

bears on the projecting portion of the associate head 9 at its left-hand end, and at its right-hand end is supported on a head or end piece 50^a which is secured by a set screw to the axle 7. The screw pin 30 secures the rotary tube 46 in fixed relationship with the shaft 7.

A hand operated pawl mechanism (not shown) of any suitable sort, and which may comprise a pawl 50^b operated by a handle 50^c as found in the Monarch machine, is adapted to coöperate with the ratchet wheel 50 to turn the same step-by-step, this step-by-step movement being communicated to the shaft 7 and the tubular end sections 45 and 46. A detent (not shown) engages with the teeth of the ratchet wheel 50 to maintain the connected parts in adjusted positions. This turning of the ratchet wheel 50 and tubular devices or sections 45 and 46 operates to advance the paper in line space distances through the coöperation of paper feeding mechanism which substantially corresponds, or may correspond, with the ordinary paper feeding devices of the Monarch typewriter, said paper feeding devices, however, coöperating only with the rotary devices 45 and 46 and not with the main intermediate stationary devices 10. Said mechanism comprises sections 51 of a main feed roller, said roller sections being mounted on a shaft 52 (Fig. 1) and as appears from Fig. 4 being spaced apart at the rear of the casing and so as to engage with the end devices 45 and 46. The shaft 52 is supported in arms 53 pivoted at 54 to brackets 55 on the slide bar 5. Springs 56 press the feed roller constantly toward the tubes 45 and 46. Arms 57 pivoted at 58 in the brackets 55 carry a shaft 59 which supports the sections 60 of a secondary feed roller, said sections 60 being spaced apart and caused by springs 61 to coöperate with the tubular devices 45 and 46. The feed roller sections project through openings in a curved deflector or paper apron 62 of the usual character, said paper apron being normally pressed upward by springs 63 on the arms 57, said apron being hung on a rock shaft 64 pivoted on the platen frame. Arranged above the apron 62 is a paper table 65 of the usual style. The rock shaft 64 carries lugs 66 which are adapted to coöperate with pins 67 to swing the arms 53 downward, thus releasing the feed roller 51 and causing small rolls 68 on the extended lower ends of the arms 53 to engage with the arms 57 and effect the release of the feed roller 60 and remove the pressure of the spring 63 to a large extent from the paper apron 62. The shaft 64 may be rocked for this purpose by devices of the character shown in the patent to Edwin E. Barney, No. 942,535 dated December 7th, 1909, said devices being actuated by a lever or finger piece 69. In addition to the paper feeding mechanism above described, paper

5 fingers of the usual or suitable character may be mounted on the rod 11 near the ends thereof so that the pressure rolls 70 (Fig. 1) of said paper fingers may engage with the tubular devices 45 and 46, but not with the cover plate 14.

10 The novel ribbon mechanism above described may be and preferably is employed in connection with the usual or suitable ribbon feeding and controlling devices for the regular or main ribbon and which may be briefly described in connection with Fig. 1 of the drawings. A narrow ribbon 71, which may be termed the main ribbon and 15 is the usual ribbon of the machine, is impregnated with copying ink and is mounted on spools (not shown), one at each side of the machine above the top plate and forward of the platen. Midway between the spools 20 the ribbon 71 is threaded through a vibratory ribbon carrier or vibrator 72, which is vertically disposed and supported on an upright guide 73, said guide being secured by screws 74 to a depending portion 75 of the 25 top plate 1. The lower end of the ribbon carrier or vibrator 72 is bifurcated and carries a pin 76 which co-operates with the slotted forward end of an operating lever 77 pivoted at 78 on a lug 79 depending from 30 the top plate. The rear arm of the lever 77 is formed with a slot 80 which receives a pin 81 carried at the upper end of a link 82. Said link is adapted to be actuated from the printing keys in a known manner and to be 35 moved back and forth along the slot 80 to vary the throw of the ribbon 71. As is well known the printing portion of the ribbon 71, within the control of the vibratory ribbon carrier, is normally below the printing point 40 but is vibrated up and down by the train of devices comprising the operating lever and actuating link to cover the printing point during the operation of the printing keys.

45 The printing instrumentalities are not shown but they are or may be of the usual character comprising type bars which are swung upward and rearward, causing the types to act against the front face of the platen 17 which is further adapted to be 50 moved between letters by the usual spring drum and escapement devices.

55 The work sheet or master sheet shown in Fig. 1 and designated by the numeral 83 is of a width sufficient to extend the full length of the stationary casing 10 and beyond the same so that the side margin of said sheet may be within the control of the paper feeding mechanism or devices comprising the rollers 51, 60 and 70. In the 60 style of work for which the present form of this invention is particularly designed the work sheet 83 is a blank printed after the manner of the usual way bill and divided into columns headed "Consignor," "Consignee-Marks," "No. Pkgs.," "Articles," "Weight," "Rate," "Freight," "Advances," "Pre-Paid," etc. Prior to introducing the work sheet into the machine the feeding devices are released so that the work sheet may be passed around the casing and the 70 first line that is to receive writing brought opposite the printing point without affecting any of the other parts. After the work sheet has been thus adjusted the lever or finger piece 69 is operated to restore the 75 feed rollers 51 and 60 to operative position. It will probably not be necessary to release and restore the pressure rolls 70 on introducing the sheet, but if found desirable this can be done by hand in the usual way. 80 From Fig. 1 it will be apparent that the work sheet 83 passes upward over the printing point and between the main ribbon 71 and the auxiliary ribbon 20 so that when the printing instrumentalities are operated the 85 front face of said work sheet will receive type impressions through the main ribbon 71 while the rear face of said work sheet will receive corresponding negative impressions from the supplementary ribbon 20. 90 When the first line of writing has been completed the usual line spacing handle may be operated, causing the pawl (not shown) to act on the ratchet wheel 50, turning said ratchet wheel and also turning the rotary 95 tubes 45 and 46. During this turning the paper feeding devices will co-operate with said tubes to advance the work sheet through a line space distance. Furthermore, the turning of the ratchet wheel 50 100 operates through the shaft 7 to cause the driving gears 25 to turn in the present instance the upper gear wheels 24, thereby giving a rotary movement to the upper ribbon spools 21, 23 in the direction of the 105 arrow in Fig. 1, causing the supplementary ribbon 20 to wind on said spool and to unwind a corresponding amount from the lower spool. This movement of the supplementary ribbon is sufficient to bring a fresh 110 portion of the ribbon opposite the printing line. If from time to time pending the completion of the work sheet or master sheet, it is necessary to remove the same from the machine and thereafter re-introduce said 115 sheet, it should be done while the paper feeding devices are in released position in order not to feed the supplementary ribbon except through regular unit distances of movement. When the master sheet has been 120 fully completed, it will contain two sets of impressions of the work, one set on the back of the master sheet and one on the front of the master sheet, said impressions being in copying ink. As has been described, the 125 master sheet may be then introduced in the middle of a pile containing as many as a dozen or fourteen sheets of tissue and press copied on the tissue sheets in the usual manner. By this method I have found in prac- 130

tice that twelve or fourteen good typewritten press copies of the work may be obtained.

The supplementary ribbon spools herein shown have a ribbon capacity equivalent to about one hundred and thirty linear feet of half inch ribbon and in practice will, under ordinary conditions, outlast two of the usual half inch main ribbons.

10 In case it is necessary to make an erasure to correct an error or for other purposes, the master sheet must be removed from the machine and the imprints on both the front and back faces separately erased.

15 It will be noted that the side margins of the master sheet where they coöperate with the paper feeding devices are blank. These margins may be used for notes and one of them, usually the left-hand one, to coöperate 20 with binding devices, said master sheets usually being filed away in binders for reference purposes.

It will further be observed that by my present invention I provide in combination 25 with the platen, means for supporting a ribbon as wide at least as the length of the printing line on the platen and means for feeding said ribbon transversely of the printing line; that said last named means 30 is automatically operative, being controlled by the means for line spacing the work sheet; that means are provided for reversing the direction of the longitudinal feed of the ribbon; that associated with said reversing means are means for automatically 35 indicating when a predetermined point in the feed of the ribbon has been reached; that this indicating means comprises a visual signal which is operated by a member, 40 in the present case 38, which member is adapted to be turned by gravity and also by the coils of ribbon; that when turned by the ribbon coils, said member moves said visual signal into indicating position; that 45 the ribbon carrying means are arranged at opposite sides of the platen and extend substantially the full length thereof; that said ribbon carrying means comprise in the present instance a pair of spools provided with 50 detachable flanges; that one of the spools in the present instance is arranged above the platen and the other below the platen, the platen being that of a front-strike machine; that the ribbon carrying means or spools 55 are movable bodily with the platen so that the bodily relationship between the platen and the spools is unvarying although the spools may turn on their axes for feeding the ribbon; that the line spacing means are 60 operative independently of the platen and comprise a ratchet wheel and a shaft; that the ribbon feeding mechanism is connected with said shaft and through it with said ratchet wheel, said ribbon feeding mechanism including gears on said shaft and gears

on said ribbon spools; that the shaft and the ratchet wheel are separate from the platen and independent thereof, so that the ribbon may be fed across the face of the platen transversely of the printing line while the 70 platen is stationary; that the ribbon above referred to, which is in the present instance a supplementary ribbon, constantly covers the printing point on the platen; that associated with the supplementary ribbon is 75 a second ribbon or what may be termed a main ribbon which is provided with vibrating devices for moving it up and down to cover the printing point; that the vibrating devices operate independently of the 80 platen as well as of the line spacing devices and also of the ribbon feeding mechanism of the supplementary ribbon; that the line feeding devices advance the work sheet between the main and supplementary ribbon 85 so that said work sheet may receive simultaneous impressions on its front and back from the two ribbons; that a hollow casing is provided combined with means for feeding an ink ribbon within said casing and 90 means for feeding a work sheet outside or without said casing; that means for feeding an ink ribbon within said casing operate independently of said casing; that means for feeding a work sheet outside said casing operate independently of said casing; that means for feeding a work sheet outside the casing and means for feeding an ink ribbon inside the casing are connected so that when 95 one feeding means is actuated the other is 100 automatically operated; that the hollow casing contains a platen, an ink ribbon inside the casing being fed over the platen, and a work sheet outside the casing being also fed over the platen; that a member is provided, 105 which, in the present instance, occupies the space generally occupied by the regular platen of the machine, said member comprising movable end sections and an intermediate section which is relatively stationary; that means coöperate with said end sections for advancing a work sheet line by line over said intermediate stationary section; that the member in the present instance is cylindrical and the movable end sections are 110 adapted to rotate, said end sections or rotary devices being connected so that they move together; that feed rolls coöperate with the end sections; that rotary line feeding devices comprising feed rollers and the 115 end sections are operated independently of the platen and of the stationary intermediate or central section or tubular device or tube; that a platen carrier or movable frame carries a platen and ribbon spools, the ribbon spools being connected with paper feeding means whereby the ribbon between the spools is fed automatically when the paper feeding means is actuated; that in the present instance the ribbon spools are arranged 120 125 130

on the movable frame or platen carrier so that their axes are parallel with the writing line on the platen carried by said movable frame; that means are provided for controlling another ribbon, said means being independent of said frame; that in the present instance said other ribbon is vibrated up and down at printing operation; that means operate to feed a work sheet over the casing, 10 tube or intermediate section between the two ribbons; that the mechanism for the vibratory ribbon is outside the casing and the mechanism for the other or supplementary ribbon is inside the casing; that the platen 15 is detachably secured within the casing to a shaft which passes through the casing and supports the same; and that paper is fed over the casing and across the platen, the printing face of the platen being accessible 20 through a slot extending lengthwise of the casing.

While I have described the preferred embodiment of my invention and explained one of the ways in which it may be used to

25 advantage, it is to be understood that the particulars of said invention may be embodied in other forms besides that shown and that said invention may be used in other ways besides the one described herein.

30 What I claim as new and desire to secure by Letters Patent, is:—

1. In a typewriting machine, the combination of a platen movable lengthwise of the lines of print, means for feeding a ribbon past the printing point independently of the platen, and line spacing means for simultaneously advancing a work sheet over the platen; said line spacing means being operative independently of the platen.

40 2. In a typewriting machine, the combination of a platen, means for supporting a ribbon as wide at least as the length of the printing line, means for feeding said ribbon transversely of the printing line, line spacing means for advancing a work sheet

45 from line to line independently of the platen, and means automatically operative by said line spacing means for feeding said ribbon transversely of the printing line.

50 3. In a typewriting machine, the combination of a platen, line spacing means operative independently of the platen for moving the paper relatively thereto, and ribbon feeding means operative automatically by said line spacing means.

4. In a typewriting machine, the combination of a platen movable lengthwise of the printing line, line spacing mechanism comprising a ratchet wheel operative independently of said platen for line spacing purposes, and ribbon feeding mechanism connected with said ratchet wheel.

55 5. In a typewriting machine, the combination of a platen movable lengthwise of the printing line, line spacing mechanism inde-

pendent of said platen comprising a ratchet wheel and a shaft connected thereto but separate from the platen, and ribbon feeding means connected to said shaft.

6. In a typewriting machine, the combination of a platen movable lengthwise of the printing line, line spacing mechanism independent of said platen and comprising a ratchet wheel and a shaft connected thereto but separate from the platen, ribbon spools, 75 and connections between said ribbon spools and said shaft.

7. In a typewriting machine, the combination of a platen movable lengthwise of the printing line, line spacing mechanism independent of said platen and comprising a ratchet wheel and a shaft connected thereto but separate from the platen, ribbon spools, gear wheels adapted to connect each of said ribbon spools to said shaft, and means operative on certain of said gear wheels to connect said ribbon spools in alternation with said shaft.

8. In a typewriting machine, the combination of a platen movable lengthwise of the printing line, line spacing mechanism independent of said platen and comprising a ratchet wheel and a shaft connected thereto but separate from the platen, ribbon spools, gear wheels adapted to connect each of said ribbon spools to said shaft, means operative on certain of said gear wheels to connect said ribbon spools in alternation with said shaft, and means operative automatically to indicate when said last recited means should be operated.

9. In a typewriting machine, the combination of a movable platen, ribbon carrying means bodily movable with said platen so that the bodily relationship between said means and said platen is constant, and means operative on said ribbon carrying means for feeding the ribbon while the platen is stationary.

10. In a typewriting machine, the combination of a movable platen, ribbon carrying means arranged at opposite sides thereof and movable with said platen so as to maintain unvarying bodily relationship therewith, and means for feeding the ribbon 115 transversely of the platen while the platen is stationary.

11. In a typewriting machine, the combination of a platen, ribbon spools arranged with their axes parallel with the writing line on said platen, said ribbon spools having an unvarying bodily relationship with said platen, and means for feeding the ribbon from one spool to the other while the platen remains stationary.

12. In a typewriting machine, the combination of a platen, ribbon spools arranged with their axes parallel with the writing line on said platen, said ribbon spools having an unvarying bodily relationship with 130

- said platen, and means for feeding the ribbon across the face of the platen transversely of the printing line while the platen is stationary.
- 5 13. In a typewriting machine, the combination of a platen, a ribbon, a vibratory ribbon carrier for supporting the ribbon and operative to move said ribbon toward and from the printing point on the platen, a 10 supplementary ribbon constantly covering the printing point on the platen, means for moving said supplementary ribbon transversely of the printing line, and means for feeding a work sheet between the two ribbons to receive impressions front and back.
- 15 14. In a typewriting machine, the combination of a platen, a ribbon, a vibratory ribbon carrier for supporting the ribbon and operative to move said ribbon toward and 20 from the printing point on the platen, a supplementary ribbon constantly covering the printing point on the platen, means for moving said supplementary ribbon transversely of the printing line independently 25 of the platen, and means for line feeding a work sheet independently of the platen between said two ribbons.
15. In a typewriting machine, the combination of a platen, a ribbon, a vibratory 30 ribbon carrier for supporting the ribbon and operative to move said ribbon toward and from the printing point on the platen, a supplementary ribbon constantly covering the printing point on the platen, means for 35 moving said supplementary ribbon transversely of the printing line independently of the platen, and means for line feeding a work sheet between said two ribbons, said ribbon feeding means being connected with 40 the line feeding means.
16. In a front-strike type writing machine, the combination of a platen, a pair of ribbon spools, a supplementary ribbon, the axes of said spools being parallel with 45 the printing line and the axis of one spool being above the printing line and the axis of the other below the printing line, the supplementary ribbon passing from one ribbon spool to the other over the platen and 50 constantly covering the printing point thereon, and vibratory mechanism for a main ribbon.
17. In a front-strike typewriting machine, the combination of a platen, a pair 55 of ribbon spools, a supplementary ribbon, the axes of said spools being parallel with the printing line and the axis of one spool being above the printing line and the axis of the other below the printing line, the 60 supplementary ribbon passing from one ribbon spool to the other over the platen and constantly covering the printing point thereon, vibratory mechanism for a main ribbon, and line feeding means for advancing the 65 work sheet between the main and supple-
- mentary ribbons so that said work sheet may receive simultaneous impressions on its front and back from said ribbons.
18. In a front-strike typewriting machine, the combination of a platen, a pair of ribbon spools, a supplementary ribbon, the axes of said spools being parallel with the printing line and the axis of one spool being above the printing line and the axis of the other below the printing line, the supplementary 70 ribbon passing from one ribbon spool to the other over the platen and constantly covering the printing point thereon, vibratory mechanism for a main ribbon, line feeding means for advancing the work sheet between the main and supplementary ribbon so that said work sheet may receive simultaneous impressions on its front and back from said ribbons, and pawl and ratchet mechanism 75 for line feeding the work sheet independently of the platen, the work sheet passing between the main and supplementary ribbons.
19. In a typewriting machine, the combination of a hollow casing, means for feeding an ink ribbon within said casing, the ribbon being inclosed within the casing but exposed to the types through a slot in said casing, and means for feeding a work sheet that is 80 outside said casing.
20. In a typewriting machine, the combination of a hollow casing, an inking ribbon, means for feeding said ink ribbon within said casing independently of said casing, the ribbon being inclosed within the casing but exposed to the types through a slot in said casing, and means for feeding a work sheet that is outside said casing and independently 85 thereof.
21. In a typewriting machine, the combination of a hollow casing, means for feeding a work sheet that is outside of said casing, an inking ribbon, and means connected with said last recited means and operative 90 thereby to feed said ink ribbon within said casing.
22. In a typewriting machine, the combination of a casing, a platen, an inking ribbon, means for feeding said ink ribbon over said platen within said casing, and means for feeding a work sheet that is outside said casing over said platen.
23. In a typewriting machine, the combination of a casing, a platen, an inking ribbon, means for feeding said ink ribbon over 100 said platen within said casing, and means for feeding a work sheet that is outside said casing over said platen, said paper feeding and ribbon feeding means being connected so as to be simultaneously operative.
24. In a typewriting machine, the combination of a member comprising movable end sections and an intermediate stationary section, and means co-operative with said end sections for advancing a work sheet line by 105

- line over said intermediate stationary section.
25. In a typewriting machine, the combination of a cylindrical member comprising 5 rotary end sections and a stationary intermediate section, and means coöperative with said rotary sections for advancing a work sheet line by line over said intermediate stationary section.
- 10 26. In a typewriting machine, the combination of a pair of connected cylindrical rotary devices, a stationary cylindrical device intermediate said rotary devices, the three devices having coincident axes, and means 15 for turning said rotary devices step-by-step to line feed a work sheet over said stationary device.
- 20 27. In a typewriting machine, the combination of a tubular member comprising rotary end sections and a stationary intermediate section, a platen within said intermediate section, and line feeding devices coöperative with said end sections independently of said intermediate section.
- 25 28. In a typewriting machine, the combination of a tubular member comprising rotary end sections and an intermediate stationary section, a platen within said stationary section, supplementary ribbon feeding 30 mechanism within said member, and means for operating said mechanism when said end sections are turned.
- 35 29. In a typewriting machine, the combination of a movable frame, a platen thereon, means for feeding paper independently of 40 said platen, ribbon spools on said frame, and connections between said ribbon spools and said paper feeding means whereby the ribbon is fed automatically.
- 45 30. In a typewriting machine, the combination of a movable frame, a platen thereon, means independent of said platen for feeding paper, ribbon spools on said frame, connections between said ribbon spools and said 50 paper feeding means whereby the ribbon is fed automatically, and means for controlling another ribbon independent of said frame.
- 55 31. In a typewriting machine, the combination with a slotted casing, a platen mounted 55 within said casing opposite the slot, a ribbon within said casing coöperative with said platen, a ribbon exterior of said casing coöperative with said platen, and means for feeding a work sheet over said casing between the two ribbons.
- 60 32. In a typewriting machine, the combination of a cylindrical hollow casing having a slot, a platen within said casing, feed rollers for advancing the paper over said 65 casing across said platen, and ribbon mechanism for two ribbons, one within said casing and one without said casing.
- 65 33. In a typewriting machine, the combination of a frame, a shaft thereon, a member comprising three sections mounted on 70 said shaft, means for holding the middle section stationary, the end sections being rotatable with said shaft, hand operated means for turning said shaft and said end sections, and a feed roll coöperative with said end sections.
- 75 34. In a front-strike typewriting machine, the combination of a frame, a shaft thereon, a hollow cylindrical member mounted on said shaft and comprising rotary end sections and a stationary central section, paper feeding mechanism comprising rollers coöperative with said end sections at the rear lower sides thereof and also comprising rollers coöperative with the front lower sides 80 of said end sections, said central section being provided at its front face with a longitudinal slot, an anvil platen detachably mounted within said central section opposite said slot, means within said member for 85 feeding a ribbon over said platen, and ribbon vibrating means exterior of said casing.
- 90 35. In a typewriting machine, the combination of a frame, a shaft thereon, means for turning said shaft step-by-step, a member 95 on said shaft and comprising three sections, the end sections being rotatable with said shaft and the central section being stationary, ribbon spools within said member, said ribbon spools being provided with gears, driving gears on said shaft, and hand operated means for moving said driving gears longitudinally of said shaft to engage with and disengage from the gears on said ribbon spools.
- 100 36. In a typewriting machine, the combination of a hollow casing, a shaft on which said casing is mounted, spools within said casing carrying gears, a driving gear on said shaft, and hand operated means for connecting said driving gear alternately with the gears on said spool, said last named means comprising a hand controlled slide rod.
- 105 37. In a typewriting machine, the combination of ribbon spools, turning means, means for connecting the first means with said ribbon spools alternately, and means for indicating to the operator when said last recited means should be operated, said 110 indicating means comprising a rotary member controlled by gravity and by the cores of ribbon and further comprising a visual signal operated by said rotary member.
- Signed at Syracuse, in the county of 115 Onondaga and State of New York, this 29th day of December A. D. 1909.
